UNITED STATES PATENT OFFICE.

WILLIAM F. GRUPE, OF NORTH BERGEN, NEW JERSEY, ASSIGNOR TO ENDLESS BELT CORPORATION, INC., A CORPORATION OF NEW YORK.

WOVEN FABRIC.

1,319,768.

Specification of Letters Patent. Patented Oct. 28, 1919.

Application filed January 25, 1918. Serial No. 213,627.

To all whom it may concern:

Be it known that I, WILLIAM F. GRUPE, a citizen of the United States of America, residing at Hudson Boulevard, North Bergen, New Jersey, have invented certain new and useful Improvements in Woven Fabrics, of which the following is a specification.

This invention relates to tube belts or forming bands for cigarette making machines.

An object of this invention is to provide a construction of tube belts or forming bands for cigarette making machines of greater effective life. In the use of tube belts or forming bands, for making cigarettes, a shoe or former is employed through which the belt or band travels. In such use of tube belts a strip of paper of indefinite length is fed on the belt, and the cigarette tobacco fed on the strip, and upon travel of the belt through the shoe, the belt is curved to form a tube, thereby "rolling" the cigarette paper and tobacco contained therein, and upon application of adhesive, a cigarette of indefinite length is formed, which is cut to desired lengths to form individual cigarettes.

Under such circumstance of use, the belt is brought into frictional engagement with the sides of the shoe and owing to the woven structure of heretofore employed belts, the life of the belt is of short duration.

In accordance with this invention, the belt is woven endlessly and the woven structure of the belt is formed of warp and weft threads arranged one under and one over, respectively, for the purpose of attaining flexible edge portions of the band, extending respectively lengthwise of the band, and for the additional purpose of imparting greater tensile strength to the central portion of the band, extending lengthwise of the band, the central portion is woven of double warp threads passing under and over single weft threads. The warp threads are preferably of substantially uniform "thickness" or diameter and of a continuous thread extending in convolutions, each convolution being substantially the length of the resultant belt. The weft threads are also preferably of substantially uniform "thickness" or diameter.

Further features and objects of the inven-

tion will be more fully understood from the following description and the accompanying drawings, in which—

55

Figure 1 shows diagrammatically an endlessly woven cigarette belt embodying my invention; and

Fig. 2 is a detail plan view, on an enlarged scale, of a preferred form of the invention, showing the weaving structure.

Referring to the drawings, the belt 1 is continuous, and preferably continuously woven and accordingly without any termination. The width and length of the belt are 65 varied, as desired.

This invention pertains particularly to belts for use in cigarette making machines of the usual type, embodying a forming shoe through which the belt passes. The belt 70 serves to feed a strip of paper of indefinite length, on which is fed the cigarette tobacco.

Upon travel of the belt through the forming shoe, the edge portions of the belt are curved upwardly, to thereby "roll" the 75 paper strip and tobacco contained thereon into a tube or cigarette of indefinite length, which is cut by suitable severing means into individual cigarettes. Such belt is known in the trade as a forming band or tube belt.

80

I have discovered that the provision of a plurality of warp threads for the central portion of the belt, passing longitudinally of the belt, passing under and over the single weft threads, and the weft threads for such 85 central portion passing under and over such plurality of warp threads, effects a great increase in the tensile strength of the resultant belt and a consequent increased life of the belt. Such construction serves also to 90 maintain a uniform feeding of the strip of paper and to maintain a uniform discharge of the formed cigarette through the forming shoe.

As indicated in Fig. 2, the edge portions 95 of the belt are preferably formed of a weaving structure comprising single weft threads passing under and over single warp threads and single warp threads passing under and over single weft threads. Such preferred 100 construction effects increased pliability of the oppositely disposed edge portions of the belt, whereby the curving action of the belt in the forming shoe is enhanced, with de-

creased frictional engagement with the curved sides of the forming shoe, thereby further increasing the life of the belt.

In the specific form of the invention shown in Fig. 2, the belt is endlessly woven by winding the warp threads 2 continuously as convolutions, each convolution being substantially equal to the length of the resultant belt, the weft threads 3 being successively interlaced therewith to form the endlessly woven belt. The weaving structure is preferably of the simple weave, that is, the weft threads and warp threads extending substantially at right angles to one another, as disclosed in my co-pending application entitled *Cigarette conveyer band*, Serial Number 137,949, filed by me on the 20th day of December, 1916.

The weaving structure of the central portion 6 of the belt 1 as shown in Fig. 2, comprises two single warp threads 7, 7, whereas the outer or edge portions of the belt comprise but single threads 8. The weft threads 9 for the central portion 6 of the belt are passed as single threads under and over such two single warp threads 7, and for the outer or edge portions, the weft threads 7 pass under and over single warp threads 8.

30 The band or belt is subjected to a finishing treatment under increased temperature condition and with or without a suitable binding or finishing material, as understood by the art.

35 The fabric embodying the present invention is advantageous in that the maximum strength of the warp and weft threads is fully preserved after weaving. The relation of the direction of length of the warp and the weft, as above described, materially increases the length of the life of the belt, particularly, as I have discovered, when employed as a conveyer in cigarette making machines.

45 It will be understood that the weft or "picks" may be increased to two or more single threads if desired and that the direction of extension may be transverse of the direction of length of the fabric other than at right angles.

50 Whereas I have described my invention by reference to specific forms thereof, it will be understood that many changes and modifications may be made without departing from the spirit of the invention as defined by the appended claims.

I claim:

1. A cigarette forming band, woven end-

lessly comprising an inner portion having a weaving structure of single weft threads 60 each passing under and over two warp threads, and of warp threads each passing under and over single weft threads and outer oppositely disposed edge portions having a weaving structure of single warp 65 threads passing under and over single weft threads and single weft threads passing under and over single warp threads.

2. A cigarette forming band, woven endlessly, comprising an edge portion having 70 a weaving structure of each weft thread passing under one and over one warp thread and of each warp thread passing under and over one weft thread and comprising a central portion having a weaving structure of 75 each weft thread passing under and over two warp threads and each warp thread passing under and over one weft thread.

3. A cigarette forming band comprising 80 opposite edge portions, each edge portion 85 having a weaving structure of each weft thread passing under and over single warp threads and each warp thread passing under and over single weft threads, and a portion disposed substantially centrally of said edge 90 portions and having a weaving structure of single weft threads each passing under and over two warp threads and each warp thread passing under and over single weft threads.

4. A cigarette forming band extending endlessly, comprising edge portions having a weaving structure of single warp threads 95 passing under and over single weft threads and single weft threads passing under and over single warp threads and a central portion having a weaving structure formed of a greater number of warp threads passing under and over a lesser number of weft threads respectively and a lesser number of weft threads passing under and over a greater number of warp threads respectively.

5. An endless cigarette forming band comprising opposite edge portions, each edge portion having a weaving structure of 105 single weft threads passing under and over single warp threads and single warp threads passing under and over single weft threads and an intermediate portion having a weaving structure of single weft threads passing under and over a plurality of warp threads 110 and each warp thread passing under and over single weft threads.

In testimony whereof I have signed this specification this 12th day of January 1918.

WILLIAM F. GRUPE.
